UNITED STATES PATENT OFFICE.

HENRY T. PAISTE, OF PHILADELPHIA, PENNSYLVANIA.

TIME INDICATOR FOR GOLF COURSES.

Application filed April 29, 1922. Serial No. 557,319.

One object of my invention is to provide a simple, convenient and easily adjustable device for visibly indicating the times at which the players on a golf course, after having begun playing at definite spaced intervals, should properly reach or leave each tee, in order to maintain predetermined intervals between them and so utilize the course to its fullest capacity and in the most satisfactory manner.

Another object of my invention is to provide a time-indicating device of the type noted which shall be available for use at all of the several tees of a golf course, and which in addition to being capable of use by all of a number of players, may be conveniently and quickly adjusted so that its indications will be correct for any particular tee,—the invention contemplating especially a holder or support and an adjustable indicating member, so designed that all of its displayed time-indicating numerals may be clearly and easily noted.

These objects and other advantageous ends I attain as hereinafter set forth, reference being had to the accompanying drawings, in which,

Fig. 1 is a front elevation of a time-indicating device constructed in accordance with my invention; and

Fig. 2 is a vertical section on the line 2—2, Fig. 1; and

Figs. 3 and 4 are plans of the adjustable numeral-carrying element or elements of my device.

In the above drawings, 1 represents a suitable supporting structure in the form of a pressed up or cast metal face member 2 having mounted on its rear side one or more disc-like sheets or plates 5. The device as a whole may be supported in any suitable or desired manner, in the present instance having an eye or perforated lug 3 at its top whereby it may be hung from or attached to a sand box or other supporting structure. The sheet or plate 5 is fixed in any desired position by a clamping screw 4 threaded into the rear side of the supporting structure and this screw may be conveniently loosened when it is desired to change or adjust the plate or sheet 5. The latter is preferably maintained flat against the rear face of the member 2 by a relatively stiff backing plate 5^a mounted on the clamp screw 4 and directly engaged by a washer 4^a thereon.

The front or vertical face of the member 2 is plane and has formed through it two series of substantially rectangular openings *a* and *b*, of which those of the first series are arranged in a substantially semi-circular line above a horizontal line passing through the center from which they are equally spaced. The second series of openings *b* is arranged on a circular arc preferably concentric with that of the series *a*, but in the case illustrated this arc is struck on a radius greater than that of the openings *a* and lies below the horizontal line through the center from which they are equidistant. In the present instance I have provided seven openings *a* and five openings *b*. Obviously the number of these openings may be varied as desired without departing from my invention.

The representations of arrows or hands *c* are preferably formed on the face 2 on radial lines terminating at the several openings *a* and *b* respectively and each of these hands, which preferably have a more or less ornamental appearance, has applied to it a player-indicating numeral *d*. The numeral for the hand *c* pointing vertically upward is nought and the numerals for the other hands increase progressively by five in a clockwise direction therefrom. While the general outline of the member 2 is immaterial so far as my invention is concerned, I have illustrated and preferably use it as semi-circularly curved from a horizontal line passing through the center *e* and as having a rectangular outline below this line.

The adjustable member or plate 5, as before noted, is circular in outline and has printed or otherwise applied to one or both of its faces two concentric series of numerals *f* and *g* of which those of the first series are at such distance from its center as will render certain of them visible through the openings *b* on the supporting structure when said plate has been applied thereto as shown. Likewise the numerals of the series *g* are arranged on a circle whose diameter is such that certain of said numerals will be visible through the openings of the series *a*, and it is noted that whereas the numerals of this latter series are so printed or formed that those of its upper half are upright or in such positions as to be easily readable when the plate is supported in a vertical plane, those of the outer series *f* are relatively re-

versed or so printed or applied that those of the lower half of the said series are easily legible.

As a consequence of this arrangement of numerals, all of those of the series *f* which are at any time visible through the openings *b*, and likewise all of those of the series *g* which are visible through the openings *a*, may be clearly and conveniently noted by anyone when the face member is hung or otherwise supported in a vertical plane, regardless of the adjustment of the plate 5.

On the second or opposite side of plate or disc 5 I have in the present instance printed or formed two other concentric series of numerals *h* and *i*, of which those of the first series, like those of the series *g* on the opposite face of the plate, are so arranged as to be visible through the openings *a* and are so printed or formed that the upper half of the series is upright. Likewise the numerals of the series *i* are arranged on a circle having the same diameter as that of the series *f* and are reversed so that the lower half of the series is upright and easily legible through the openings *b*, under the conditions previously noted. The numerals of the two series *f* and *g* are so spaced in the present case that every fourth one of the lower half of the first series is visible through the openings *b* and similarly every fourth one of the upper half of the series *g* is visible through the openings *a*.

Beginning with nought, the numerals of each series successively increase, in the case shown by one, for three spaces and for each of the following three spaces likewise increase by one, there being however an increase of three between the third and the fourth, the sixth and the seventh spaces, and so on up to 57. The series of numerals *h* and *i* on the second face of the plate or disc 5 are thus omitted from the corresponding series of the other face, so that by suitably placing the disc in the holder any series of numerals, differing in amount by five and between the limits of nought and fifty-nine, may be so positioned as to be visible through the two sets of openings *a* and *b*.

With the above described arrangement of parts, a suitable number of indicating devices, such as that illustrated, are prepared, it being assumed that the various players are to begin playing at the first tee at intervals of five minutes apart, for example. At the first tee, the disc or plate 5 is so held by its clamping screw to the holder or face member that the numerals 0, 5, 10, 15, 45, 50 and 55 will be visible through the openings *a* and the numerals 20, 25, 30, 35, and 40 will be visible through the openings *b*. The various players will be assigned numbers differing by five and running from 0 to 55 and each of them will begin playing at the starting tee at the time corresponding

to the number of minutes past the hour, fixed by his assigned number.

At the second tee another one of my devices will be set up, and if it be assumed that eight minutes, for example, is required for an average player to make the distance between the first and second tees, then the plate 5 of this second device will be so set as to display the numeral 8 at the uppermost of the openings *a* opposite the arrow or hand having the nought indication. In the next space to the right will be displayed the numeral 13 adjacent the hand or arrow bearing the number 5, thus indicating for example, that the second player should reach the second tee at thirteen minutes after the hour if he began to play at five minutes after the same. Similarly the space opposite the hand bearing the numeral 10 would have displayed in it the numeral 18, that opposite the hand having the numeral 15 would show the numeral 23 and so on, thereby indicating to any player at what time he should properly arrive at the second tee, if he has played the game at the predetermined average speed.

At the third and other tees of the course are placed additional devices, each with its disc or plate 5 so adjusted as to show at a glance to each player designated by one of the numbers indicated on the hands *c*, at just what time he should properly reach any particular tee. By reason of the double series of reversely positioned numerals, it is a matter of the greatest ease to unmistakeably read or note any numeral displayed in either of the sets of openings *a* or *b*, where the reverse would be true if but a single series of numerals should be provided, since some of these would necessarily be inverted at certain portions of the device.

From the above description it will be appreciated that my indicator is of a relatively simple construction, is convenient and may be easily adjusted to give correct indications at any position on a golf course, it being obvious that the numerals on either face of the plate may be displayed through the openings by properly positioning it on its supporting structure. It is of course immaterial whether the device be made of metal, wood or other material and it may obviously be supported or mounted in any desired way without departing from my invention.

While I have illustrated a plate or disc having two series of numerals on each of its faces and have shown the numerals of each series as arranged in different groups, it is to be understood that this arrangement may be widely varied without departing from my invention, which contemplates broadly the provision of one or more adjustable indicating members or plates hav-

ing thereon at least two concentric series of time-indicating numerals oppositely disposed relatively to each other so that when used with a face member having top and bottom openings, all of the figures displayed in or through said openings will be in such positions as to be easily legible.

I claim:

1. In a time indicator for golf courses, the combination of a fixed face member; a plate pivotally mounted at the back of said fixed member; and means for securing the plate temporarily against rotation, said plate having two concentric series of time indicating numerals thereon, one series being nearer the center of rotation of the plate than the other series, the face member having two series of openings therein, one series of openings being in alignment with one of the series of numerals on the pivoted plate, and the other series of openings being in alignment with the other series of numerals on said plate, the face member having player designating characters thereon located adjacent the openings respectively.
2. In a time indicator for golf courses, the combination in a fixed member; a plate pivotally mounted at the back of said fixed member; and means at the back of said plate for holding the plate in fixed posi-

tion with respect to the face member after adjustment, said plate having two concentric series of time indicating numerals thereon, one series being nearer the center of rotation of the plate than the other series, the numerals of one series being inverted with respect to those of the other series, the face member having two series of openings, one series being in alignment with one of the series of numerals on the pivoted plate, and the other series of openings being in alignment with the other series of numerals, the face member having player designating characters positioned adjacent the openings respectively.

3. The combination in a time indicator for golf courses, of a fixed face member; a plate pivotally mounted at the back of the fixed member, said plate having two concentric series of time indicating numerals, said numerals indicating a given length of time, the length of time between the series of numerals being the same; and openings in the fixed face member aligning with the series of numerals on the plate, the face member having player designating characters thereon positioned adjacent the openings respectively.

HENRY T. PAISTE.
